UNITED STATES PATENT OFFICE.

LEBBEUS BALDWIN MILLER AND PHILIP DIEHL, OF ELIZABETH, N. J.

PITMAN.

SPECIFICATION forming part of Letters Patent No. 298,701, dated May 13, 1884.

Application filed December 8, 1883. (No model.)

To all whom it may concern:

Be it known that we, LEBBEUS BALDWIN MILLER and PHILIP DIEHL, of the city of Elizabeth, in the county of Union and State 5 of New Jersey, have made an invention of certain new and useful Improvements in Pitmen for Sewing and other Machines; and I do hereby declare that the following is a full, clear, and exact description and specification of the 10 same.

The object of this invention is to provide simple and reliable means for conveniently placing such pitman in proper operative position by passing it over a crank-shaft or onto 15 the pin or bend which forms the crank, and thereafter adjusting and taking up the wear of the hole or holes in such pitman, through one of which the crank-pin or a portion of the 20 crank to be turned passes, and through the other of which passes the driving-pin of the usual reciprocal driver; and we accomplish this by regulating the size of said hole or holes.

In the drawings, Figures 1 and 2 are front 25 views of such pitman, and Figs. 3 and 4 are edge views, Fig. 3 being partly in section.

The pitman shown as embodying and illustrating our invention is of the form usually employed to receive reciprocating motion from 30 the treadle of a sewing-machine and transmit motion to the rotary crank which actuates the band or driving wheel of such machine. The pitman A is formed with a recess or aperture, B. Secured in said pitman-head at the top 35 of said recess is the internally-threaded nut C,

made preferably of iron. The screw D, provided with the pin-extension d, passes loosely through a hollow in the pitman-head. Its thread engages and operates in the nut D, and its extension d enters and holds firmly the 40 block E, which is adapted to slide in the aperture B, and is moved by turning the screw D to regulate the extent of the aperture as desired, and held firmly by said screw and extension at the desired vertical point, being 45 also held firmly against lateral motion by said extension.

We claim as our invention—

1. In a pitman, the combination of an opening, a fixed nut formed separate from the pitman, a block adapted to slide in said opening, and a regulating-screw provided with a thread engaging said nut, and with an extension attached to said sliding-block, substantially as and for the purpose described. 55

2. The combination, with a pitman having an elongated opening, a nut fixed in said opening, and a block free to slide therein, of an adjusting-screw passing through the head of said pitman and engaging said nut, and provided with an extension entering said sliding block and holding it firmly in position and against lateral motion, substantially as described. 60

LEBBEUS BALDWIN MILLER.
PHILIP DIEHL.
